(57) **ABSTRACT**

An air conditioning system includes a plurality of indoor units installed in the same indoor space, an outdoor unit and a control device. The indoor units include respective usage-side heat exchangers capable of setting set temperatures individually. The outdoor unit includes a heat-source-side heat exchanger. The control device performs temperature control using a thermo-ON condition set in advance in accordance with the set temperatures, and relaxes the thermo-ON condition of thermo-OFF indoor units when the indoor units include both those that are thermo-ON and those that are thermo-OFF and a predetermined condition is satisfied. The predetermined condition is that at least one of the plurality of indoor units continues to be thermo-ON for a first elapsed time or longer, and at least one of the plurality of indoor units continues to be thermo-OFF for a second elapsed time or longer.

AIR CONDITIONING SYSTEM AND
CONTROL METHOD THEREOFCROSS-REFERENCE TO RELATED
APPLICATIONS

This U.S. National stage application claims priority under 35 U.S.C. §119(a) to Japanese Patent Application No. 2013-204145, filed in Japan on Sep. 30, 2013, the entire contents of which are hereby incorporated herein by reference.

TECHNICAL FIELD

The present invention relates to an air conditioning system for circulating refrigerant between a heat-source-side heat exchanger and a plurality of usage-side heat exchangers, and a method for controlling same.

BACKGROUND ART

In a conventional air conditioning apparatus or another air conditioning system, a vapor-compression refrigeration cycle is performed for circulating refrigerant in a refrigerant circuit having a compressor for compressing the refrigerant, a heat-source-side heat exchanger and usage-side heat exchanger for enabling the refrigerant to exchange heat, and a pressure-reducing mechanism for pressure-reducing the refrigerant. Among such air conditioning systems, there are those in which a plurality of indoor units including usage-side heat exchangers are disposed in the same large indoor space of, e.g., a conference hall or the like, in order to sufficiently condition the air in the same indoor space.

In an air conditioning system having a plurality of indoor units in this manner, e.g., the air conditioning apparatus disclosed in Japanese Laid-open Patent Application No. 2011-257126, operating efficiency is improved without causing the capabilities of the plurality of indoor units to be insufficient, by adjusting the operations of the outdoor unit and the plurality of indoor units.

SUMMARY

Technical Problem

However, because individual controls are performed on the plurality of indoor units individually, there are cases in which conditions arise such that, due to the operating state, among the plurality of indoor units there are both those that are thermo-ON and those that are thermo-OFF. In such cases, there are times when the operating efficiency of the system has a whole could still be improved even though the operating efficiencies of the individual indoor units is high.

An object of the present invention is for an air conditioning system in which a plurality of indoor units are disposed in the same indoor space to be made more efficient over the entire air conditioning system.

Solution to Problem

An air conditioning system according to a first aspect of the present invention comprises: a plurality of indoor units installed in the same indoor space, including respective usage-side heat exchangers, and capable of setting set temperatures individually; an outdoor unit including a heat-source-side heat exchanger for conducting heat exchange with refrigerant circulating through the usage-side heat exchangers; and a control device configured so as to perform

2

temperature control of the same indoor space for each indoor unit, using a thermo-ON condition set in advance in accordance with a set temperature, and to relax the thermo-ON condition of thermo-OFF indoor units when there are both thermo-ON indoor units and thermo-OFF indoor units and a predetermined condition has been satisfied.

In the air conditioning system of the first aspect, when there are both thermo-ON indoor units and thermo-OFF indoor units, the thermo-ON condition is relaxed, whereby 10 more indoor units can be switched thermo-ON to increase the number of usage-side heat exchangers conducting heat exchange with refrigerant circulating in the heat-source-side heat exchanger. As a result, due to a greater number of thermo-ON units, heat exchange can be balanced with the 15 apparent area of all the usage-side heat exchangers together having increased, and the differential pressure between evaporation pressure and the condensation pressure of the air conditioning system can be reduced.

An air conditioning system according to a second aspect 20 of the present invention is the air conditioning system according to the first aspect, wherein the control device is configured so as to relax the thermo-ON condition without altering a thermo-OFF condition.

In the air conditioning system of the second aspect, 25 because the thermo-OFF condition is not altered even if the thermo-ON condition is relaxed, thermo-OFF can be carried out at different timings depending on the set temperature that is set in each indoor unit.

An air conditioning system according to a third aspect of 30 the present invention is the air conditioning system according to the first or second aspect, wherein the control device is configured so as to appoint the operating condition of the outdoor unit so as to satisfy the highest increase requirement among the increase requirements for air-conditioning capability from the plurality of indoor units.

In the air conditioning system of the third aspect, the outdoor unit can be operated in response to the highest requirement of air-conditioning capability from among the indoor units, and the air-conditioning capability requirements of all the indoor units are met.

An air conditioning system according to a fourth aspect of 45 the present invention is the air conditioning system according to the third aspect, wherein the control device has required temperature calculation units for calculating required evaporation temperatures or required condensation temperatures of the usage-side heat exchanger for each of the indoor units, and a target value appointing unit for appointing a target evaporation temperature on the basis of the minimum value among the required evaporation temperatures of the indoor units calculated in the required temperature calculation units, or appointing a target condensation temperature on the basis of the maximum value among the required condensation temperatures of the indoor units calculated in the required temperature calculation 50 units.

In the air conditioning system of the fourth aspect, target evaporation temperatures or target condensation temperatures can be appointed for the outdoor unit in response to the highest requirement of air-conditioning capability from 60 among the plurality of indoor units, whereby a target evaporation temperature or a target condensation temperature can be appointed which meets the air-conditioning capability requirements of all of the indoor units.

An air conditioning system according to a fifth aspect of 65 the present invention is the air conditioning system according to any of the first through fourth aspects, wherein the control device is configured so that the predetermined con-

dition is that among the plurality of indoor units, there must be at least one unit that has continued to be thermo-ON for a first elapsed time or longer, and at least one unit that has continued to be thermo-OFF for a second elapsed time or longer.

In the air conditioning system of the fifth aspect, it is possible to prevent a relaxing of the thermo-ON condition due to temporary state in which indoor units that should be thermo-ON have continued to not be thermo-ON for the first elapsed time, or a temporary state in which indoor units that should be thermo-OFF have continued to not be thermo-OFF for the second elapsed time.

An air conditioning system according to a sixth aspect of the present invention is the air conditioning system according to any of the first through fifth aspects, wherein the thermo-ON condition is a condition that the indoor units be thermo-ON when there is a predetermined temperature difference between the set temperature and a control temperature, and the control device is configured so as to relax the thermo-ON condition by reducing the predetermined temperature difference of the thermo-ON condition.

In the air conditioning system of the sixth aspect, a relaxing of the thermo-ON condition can be achieved by a simple operation of altering the predetermined temperature difference relative to the set temperature.

An air conditioning system according to a seventh aspect of the present invention is the air conditioning system according to any of the first through sixth aspects, wherein the plurality of indoor units further include respective air blowers of which the airflow volumes directed to the usage-side heat exchangers can be adjusted; and the control device is configured so as adjust the air blowers for each indoor unit, reduce the airflow volumes when the air-conditioning capabilities are excessive, and increase the airflow volumes when the air-conditioning capabilities are insufficient.

In the air conditioning system of the seventh aspect, the air-conditioning capability of each indoor unit can be autonomously adjusted via the airflow volume of the air blower, and the air-conditioning capability can be autonomously optimized.

An air conditioning system according to an eighth aspect of the present invention is the air conditioning system according to any of the first through seventh aspects, wherein the plurality of indoor units further include respective expansion mechanisms capable of adjusting the degrees of superheat or the degrees of subcooling in the outlet sides of the usage-side heat exchangers; and the control device is configured so as to adjust the opening degrees of the expansion mechanisms in each indoor unit, reduce the degrees of superheat or degrees of subcooling when the air-conditioning capabilities are excessive, and increase the degrees of superheat or degrees of subcooling when the air-conditioning capabilities are insufficient.

In the air conditioning system of the eighth aspect, the air-conditioning capability in each indoor unit can be autonomously adjusted by adjusting the opening degree of the expansion mechanism.

An air conditioning system according to a ninth aspect of the present invention is the air conditioning system according to any of the first through eighth aspects, wherein the control device is centralized controllers which acquire data from the outdoor unit and the plurality of indoor units, and send data to the outdoor unit and the plurality of indoor units.

In the air conditioning system of the ninth aspect, the outdoor unit and the indoor units can be collectively managed by centralized controllers.

A method for controlling an air conditioning system according to a tenth aspect of the present invention is a method for controlling an air conditioning system comprising: a plurality of indoor units installed in the same indoor space, including respective usage-side heat exchangers, and capable of setting set temperatures individually; and an outdoor unit including a heat-source-side heat exchanger for conducting heat exchange with refrigerant circulating through the usage-side heat exchangers; the method for controlling an air conditioning system having a first step of causing temperature control of the same indoor space to be performed in each indoor unit, using a thermo-ON condition set in advance in accordance with the set temperatures, and a second step of relaxing the thermo-ON condition of thermo-OFF indoor units when the indoor units include both those that are thermo-ON and those that are thermo-OFF and a predetermined condition is satisfied.

In the method for controlling an air conditioning system of the tenth aspect, when there are both thermo-ON indoor units and thermo-OFF indoor units, the thermo-ON condition is relaxed, whereby more indoor units can be switched thermo-ON to increase the number of usage-side heat exchangers conducting heat exchange with refrigerant circulating in the heat-source-side heat exchanger. As a result, there are more thermo-ON indoor units, whereby heat exchange can be balanced with the apparent area of all the usage-side heat exchangers together having increased, and the differential pressure between the evaporation pressure and the condensation pressure of the air conditioning system can be reduced.

Advantageous Effects of Invention

In the air conditioning system according to the first aspect of the present invention or the method for controlling an air conditioning system according to the tenth aspect, the differential pressure between the evaporation pressure and the condensation pressure of the air conditioning system can be reduced to improve the efficiency of the entire air conditioning system.

In the air conditioning system of the second aspect, thermo-OFF can be carried out at different timings depending on the set temperature that is set in each indoor unit, and efficiency can be improved while carrying out operations conforming to the requirements of each of the indoor units.

In the air conditioning system of the third aspect, efficiency can be improved while preventing the air-conditioning capabilities from being insufficient in some indoor units.

In the air conditioning system of the fourth aspect, a target evaporation temperature or a target condensation temperature can be appointed which meets the air-conditioning capability requirements of all of the indoor units, and efficiency can be improved while preventing the air-conditioning capabilities from being insufficient in some indoor units.

In the air conditioning system of the fifth aspect, efficiency can be improved while suppressing temperature imbalances in the same indoor space.

In the air conditioning system of the sixth aspect, control of an air conditioning system that readily turns thermo-ON can be achieved in a simple manner.

In the air conditioning system of the seventh aspect, air-conditioning capabilities can be autonomously optimized via the airflow volumes of the air blowers, and loss of efficiency due to altering of the thermo-ON condition can be suppressed in each indoor unit.

In the air conditioning system of the eighth aspect, air-conditioning capabilities can be autonomously optimized via the opening degrees of the expansion mechanisms, and loss of efficiency due to altering of the thermo-ON condition can be suppressed in each indoor unit.

In the air conditioning system of the ninth aspect, the entire air conditioning system is easily harmonized.

BRIEF DESCRIPTION OF THE DRAWINGS

FIG. 1 is a circuit diagram showing the schematic configuration of an air conditioning apparatus according to an embodiment of the present invention.

FIG. 2 is a block diagram illustrating the control system of the air conditioning apparatus.

FIG. 3 is a flowchart showing the flow of energy conservation control in the air-cooling operation.

FIG. 4 is a flowchart showing the flow of energy conservation control in the air-heating operation.

FIG. 5 is a flowchart showing the flow of equalization control of the indoor unit operating states.

FIG. 6 is a graph for illustrating the actions of the indoor units under the equalization control of FIG. 5.

DESCRIPTION OF EMBODIMENTS

An air conditioning apparatus and a method for controlling same are described below, with reference to the drawings, as an example of the air conditioning system and the method for controlling same according to the present invention.

(1) Configuration of Air Conditioning Apparatus

FIG. 1 is a schematic configuration drawing of an air conditioning apparatus according to an embodiment of the present invention. The air conditioning apparatus 10 is an apparatus used to cool and warm the air in a room of a building or the like, by performing a vapor-compression refrigeration cycle operation. The air conditioning apparatus 10 comprises primarily an outdoor unit 20 as one heat source unit, indoor units 40, 50, 60 as a plurality of usage units (three in the present embodiment) connected in parallel to the outdoor unit, and a liquid refrigerant communication tube 71 and gas refrigerant communication tube 72 as refrigerant communication tubes for connecting the outdoor unit 20 and the indoor units 40, 50, 60. Specifically, a vapor-compression refrigerant circuit 11 of the air conditioning apparatus 10 of the present embodiment is configured by connecting the outdoor unit 20, the indoor units 40, 50, 60, the liquid refrigerant communication tube 71, and the gas refrigerant communication tube 72.

(1-1) Indoor Units

The indoor units 40, 50, 60 are installed in one room 1 such as, e.g., a conference room of a building by being embedded in, suspended from, or otherwise attached to the ceiling of the room, or by being mounted on or otherwise attached to a wall of the room. The indoor units 40, 50, 60 are connected to the outdoor unit 20 via the liquid refrigerant communication tube 71 and the gas refrigerant communication tube 72, and the indoor units constitute part of the refrigerant circuit 11.

Next, the configurations of the indoor units 40, 50, 60 are described. Because the indoor unit 40 and the indoor units 50, 60 have the same configuration, only the configuration of the indoor unit 40 is described here, and the configurations of the indoor units 50, 60, being denoted with symbols numbering in the fifties and sixties in place of the symbols

numbering in the forties indicating the components of the indoor unit 40, are not described.

The indoor unit 40 has primarily an indoor-side refrigerant circuit 11a constituting part of the refrigerant circuit 11 (the indoor unit 50 has an indoor-side refrigerant circuit 11b and the indoor unit 60 has an indoor-side refrigerant circuit 11c). This indoor-side refrigerant circuit 11a has primarily an indoor expansion valve 41 as an expansion mechanism and an indoor heat exchanger 42 as a usage-side heat exchanger. In the present embodiment, indoor expansion valves 41, 51, 61 are provided as expansion mechanisms to the indoor units 40, 50, 60 respectively, but the embodiment is not limited as such, and an expansion mechanism (including an expansion valve) may be provided to the outdoor unit 20, or to a connection unit independent of the indoor units 40, 50, 60 and the outdoor unit 20.

The indoor expansion valve 41 is an electric expansion valve connected to the liquid side of the indoor heat exchanger 42 in order to adjust or otherwise manipulate the flow rate of refrigerant flowing within the indoor-side refrigerant circuit 11a, and is also capable of blocking the passage of refrigerant.

The indoor heat exchanger 42 is a cross-fin-type fin-and-tube heat exchanger configured from, e.g., a heat transfer tube and numerous fins, and this heat exchanger functions as an evaporator of refrigerant to cool indoor air during an air-cooling operation, and functions as a condenser of refrigerant to heat indoor air during an air-heating operation.

The indoor unit 40 has an indoor fan 43 as an air blower for drawing indoor air into the unit, and supplying heat-exchanged indoor air as supply air into the room after the air has exchanged heat with refrigerant in the indoor heat exchanger 42. The indoor fan 43 is a fan capable of varying the airflow volume of air supplied to the indoor heat exchanger 42 within a predetermined airflow volume range, and is a centrifugal fan, multi-blade fan, or the like driven by a motor 43m composed of, e.g., a DC fan motor or the like. The indoor fan 43 can be selectively set to any of the following modes: constant-airflow-volume mode in which the airflow volume is set to one of three constant airflow volumes including low airflow having the lowest airflow volume, high airflow having the highest airflow volume, and medium airflow of an intermediate extent between low airflow and high airflow; automatic-airflow-volume-control mode in which the airflow volume is automatically varied from low airflow to high airflow in accordance with the degree of superheat SH, the degree of subcooling SC, and/or other factors; and airflow-volume-setting mode in which the airflow volume is manually varied through a remote controller or another input device. Specifically, when a user selects either "low airflow," "medium airflow," or "high airflow" using, e.g., a remote controller, the mode will be constant-airflow-volume mode in which the airflow volume is constant at low airflow, and when a user selects "automatic," the mode will be automatic-airflow-volume-control mode in which the airflow volume is varied automatically in accordance with the operating state. A description is given here of the configuration whereby the fan tap of the airflow volume of the indoor fan 43 is switched among the three levels "low airflow," "medium airflow," and "high airflow."

The indoor fan airflow volume G_a , which is the airflow volume of the indoor fan 43, can be derived from a calculation using, e.g., the rotational speed of the motor 43m as a parameter. Alternative methods include deriving the indoor fan airflow volume G_a from a calculation based on the

electric current value of the motor **43m**, deriving the indoor fan airflow volume G_a from a calculation based on the set fan tap, and other methods.

Various sensors are also provided to the indoor unit **40**. On the liquid side of the indoor heat exchanger **42**, a liquid line temperature sensor **44** is provided for detecting the temperature of the refrigerant (i.e., the refrigerant temperature corresponding to the condensation temperature T_c during the air-heating operation or the evaporation temperature T_e during the air-cooling operation). On the gas side of the indoor heat exchanger **42**, a gas line temperature sensor **45** is provided for detecting the temperature of the refrigerant. On the intake port side for indoor air of the indoor unit **40**, an indoor temperature sensor **46** is provided for detecting the temperature of indoor air flowing into the unit (i.e., the indoor temperature T_r). For example, thermistors can be used for the liquid line temperature sensor **44**, the gas line temperature sensor **45**, and the indoor temperature sensor **46**. The indoor unit **40** also has an indoor-side control device **47** for controlling the actions of the components constituting the indoor unit **40**. The indoor-side control device **47** has an air-conditioning capability calculation unit **47a** for calculating the current air-conditioning capability and other parameters in the indoor unit **40**, and a required temperature calculation unit **47b** for calculating, on the basis of the current air-conditioning capability, the required evaporation temperature T_{er} or required condensation temperature T_{cr} needed to achieve said capability (see FIG. 2). The indoor-side control device **47**, which has a microcomputer (not shown), a memory **47c**, and or the like provided in order to control the indoor unit **40**, is designed to be capable of exchanging control signals and the like with a remote controller (not shown) for individually operating the indoor unit **40**, and exchanging control signals and the like with the outdoor unit **20** via a transmission line **80a**.

(1-2) Outdoor Unit

The outdoor unit **20** is installed on the outside of a building or the like and is connected to the indoor units **40**, **50**, **60** via the liquid refrigerant communication tube **71** and the gas refrigerant communication tube **72**, and the outdoor unit **20** together with the indoor units **40**, **50**, **60** constitutes the refrigerant circuit **11**.

Next, the configuration of the outdoor unit **20** is described. The outdoor unit **20** has primarily an outdoor-side refrigerant circuit **11d** constituting part of the refrigerant circuit **11**. This outdoor-side refrigerant circuit **11d** has primarily a compressor **21**, a four-way switching valve **22**, an outdoor heat exchanger **23** as a heat-source-side heat exchanger, an outdoor expansion valve **38** as an expansion mechanism, an accumulator **24**, a liquid-side shutoff valve **26**, and a gas-side shutoff valve **27**.

The compressor **21** is a compressor of which the operating capacity can be varied, and is a positive-displacement compressor driven by a motor **21m** of which the rotational speed is controlled by an inverter. There is only one compressor **21** of the outdoor unit **20** depicted here, but there can be two or more compressors in cases such as when there is a large number of indoor units connected.

The four-way switching valve **22** is a valve for switching the direction of refrigerant flow. During the air-cooling operation, the four-way switching valve **22** connects the discharge side of the compressor **21** and the gas side of the outdoor heat exchanger **23**, and connects the intake side of the compressor **21** (specifically, the accumulator **24**) and the gas refrigerant communication tube **72** side (air-cooling operation state: refer to the solid lines of the four-way switching valve **22** in FIG. 1), in order to make the outdoor

heat exchanger **23** function as a condenser of the refrigerant compressed by the compressor **21** and the indoor heat exchangers **42**, **52**, **62** function as evaporators of the refrigerant condensed in the outdoor heat exchanger **23**. During the air-heating operation, the four-way switching valve **22** can connect the discharge side of the compressor **21** and the gas refrigerant communication tube **72** side, and connects the intake side of the compressor **21** and the gas side of the outdoor heat exchanger **23** (air-heating operation state: refer to the dashed lines of the four-way switching valve **22** in FIG. 1), in order to make the indoor heat exchangers **42**, **52**, **62** function as condensers of the refrigerant compressed by the compressor **21** and the outdoor heat exchanger **23** function as an evaporator of the refrigerant condensed in the indoor heat exchangers **42**, **52**, **62**.

The outdoor heat exchanger **23** is, e.g., a cross-fin-type fin-and-tube heat exchanger, and is a device for enabling heat exchange between air and refrigerant in order to use air as a heat source. The outdoor heat exchanger **23** is a heat exchanger that functions as a condenser of refrigerant during the air-cooling operation, and functions as an evaporator of refrigerant during the air-heating operation. The gas side of the outdoor heat exchanger **23** is connected to the four-way switching valve **22**, and the liquid side is connected to the outdoor expansion valve **38**.

The outdoor expansion valve **38** is an electric expansion valve disposed on what is during the air-cooling operation the downstream side of the outdoor heat exchanger **23** in the direction of refrigerant flow in the refrigerant circuit **11**, in order to adjust the pressure, flow rate, and/or other characteristics of the refrigerant flowing within the outdoor-side refrigerant circuit **11d**. In other words, the outdoor expansion valve **38** is connected to the liquid side of the outdoor heat exchanger **23**.

The outdoor unit **20** has an outdoor fan **28** as an air blower for drawing outdoor air into the unit, and discharging the air out of the room after the air has exchanged heat with the refrigerant in the outdoor heat exchanger **23**. This outdoor fan **28** is a fan capable of varying the airflow volume of air supplied to the outdoor heat exchanger **23**, and is a propeller fan or the like driven by a motor **28m** composed of, e.g., a DC fan motor or the like.

The liquid-side shutoff valve **26** and the gas-side shutoff valve **27** are valves provided to the ports connecting with the liquid refrigerant communication tube **71** and the gas refrigerant communication tube **72**. The liquid-side shutoff valve **26** is disposed on what is during the air-cooling operation the downstream side of the outdoor expansion valve **38** and the upstream side of the liquid refrigerant communication tube **71** in the direction of refrigerant flow in the refrigerant circuit **11**, and is capable of blocking the passage of refrigerant. The gas-side shutoff valve **27** is connected to the four-way switching valve **22** and is capable of blocking the passage of refrigerant.

The outdoor unit **20** is provided with an intake pressure sensor **29** for detecting the intake pressure of the compressor **21** (i.e., the refrigerant pressure corresponding to the evaporation pressure P_e during the air-cooling operation), a discharge pressure sensor **30** for detecting the discharge pressure of the compressor **21** (i.e., the refrigerant pressure corresponding to the condensation pressure P_c during the air-heating operation), an intake temperature sensor **31** for detecting the intake temperature of the compressor **21**, and a discharge temperature sensor **32** for detecting the discharge temperature of the compressor **21**. Provided on the intake port side for outdoor air of the outdoor unit **20** is an outdoor temperature sensor **36** for detecting the temperature

of outdoor air (i.e., the outdoor temperature) flowing into the unit. For example, thermistors can be used for the intake temperature sensor 31, the discharge temperature sensor 32, and the outdoor temperature sensor 36. The outdoor unit 20 also has an outdoor-side control device 37 for controlling the actions of the components constituting the outdoor unit 20. The outdoor-side control device 37 has a target value appointing unit 37a for appointing a target evaporation temperature Tet or a target condensation temperature Tct (alternatively, a target evaporation temperature difference Δ Tet or a target condensation temperature difference Δ Tct) for controlling the operating capacity of the compressor 21, as shown in FIG. 2. The outdoor-side control device 37 also has a microcomputer (not shown) provided in order to control the outdoor unit 20, a memory 37b, an inverter circuit for controlling the motor 21m, and/or the like, and the outdoor-side control device 37 is designed to be able to exchange control signals and the like with the indoor-side control devices 47, 57, 67 of the indoor units 40, 50, 60 via the transmission line 80a. Specifically, an operation control device 80 for performing operation control on the entire air conditioning apparatus 10 is configured from the indoor-side control devices 47, 57, 67, the outdoor-side control device 37, and the transmission line 80a connecting the control devices.

The operation control device 80 is connected so as to be able to receive the detection signals of the intake pressure sensor 29, the discharge pressure sensor 30, the intake temperature sensor 31, the discharge temperature sensor 32, the outdoor temperature sensor 36, the liquid line temperature sensors 44, 54, 64, the gas line temperature sensors 45, 55, 65, and the indoor temperature sensors 46, 56, 66, as shown in FIG. 2. The operation control device 80 is also connected to the compressor 21, the four-way switching valve 22, the outdoor fan 28, the outdoor expansion valve 38, the indoor expansion valves 41, 51, 61, the indoor fans 43, 53, 63, and other components so as to be able to control the outdoor unit 20 and the indoor units 40, 50, 60 on the basis of these detection signals and other factors. Furthermore, various data for controlling the air conditioning apparatus 10 is stored in the memories 37b, 47c, 57c, 67c constituting the operation control device 80.

(1-3) Refrigerant Communication Tube

The refrigerant communication tubes 71, 72 are refrigerant tubes constructed on site when the air conditioning apparatus 10 is installed in a building or another installation location, and tubes of various lengths and/or diameters are used depending on the installation location, the combination of the models of the outdoor unit and indoor units, and other installation conditions. For example, when a new air conditioning apparatus 10 is installed in a building or the like, the air conditioning apparatus 10 is filled with the proper quantity of refrigerant depending on the lengths and diameters of the refrigerant communication tubes 71, 72, and/or other installation conditions.

As described above, the indoor-side refrigerant circuits 11a, 11b, 11c, the outdoor-side refrigerant circuit 11d, and the refrigerant communication tubes 71, 72 are connected, constituting the refrigerant circuit 11 of the air conditioning apparatus 10. The air conditioning apparatus 10 is designed so that operation is performed by the operation control device 80 configured from the indoor-side control devices 47, 57, 67 and the outdoor-side control device 37, while the air-cooling operation and the air-heating operation are switched by the four-way switching valve 22, and the various devices of the outdoor unit 20 and the indoor units

40, 50, 60 are controlled in accordance with operating loads of the indoor units 40, 50, 60.

(2) Actions of Air Conditioning Apparatus

During the air-cooling operation and the air-heating operation in the air conditioning apparatus 10, indoor temperature control is performed on the indoor units 40, 50, 60, in which the indoor temperatures Tr1, Tr2, Tr3 are brought nearer to set temperatures Ts1, Ts2, Ts3 set individually for each of the indoor units 40, 50, 60 by a user via a remote controller or another input device. In this indoor temperature control, when the indoor fans 43, 53, 63 are set to automatic-airflow-volume-control mode, the airflow volume of the indoor fan 43 and the opening degree of the indoor expansion valve 41 are adjusted so that the indoor temperature Tr1 approaches the set temperature Ts1, the airflow volume of the indoor fan 53 and the opening degree of the indoor expansion valve 51 are adjusted so that the indoor temperature Tr2 approaches the set temperature Ts2, and the airflow volume of the indoor fan 63 and the opening degree of the indoor expansion valve 61 are adjusted so that the indoor temperature Tr3 converges on the set temperature Ts3.

When the indoor fans 43, 53, 63 are set to constant-airflow-volume mode, the opening degree of the indoor expansion valve 41 is adjusted so that the indoor temperature Tr1 approaches the set temperature Ts1, the opening degree of the indoor expansion valve 51 is adjusted so that the indoor temperature Tr2 approaches the set temperature Ts2, and the opening degree of the indoor expansion valve 61 is adjusted so that the indoor temperature Tr3 approaches the set temperature Ts3. What is controlled by adjusting the opening degrees of the indoor expansion valves 41, 51, 61 is the degree of superheat in the outlets of the indoor heat exchangers 42, 52, 62 during the air-cooling operation, and the degree of subcooling in the outlets of the indoor heat exchangers 42, 52, 62 during the air-heating operation.

(2-1) Air-Cooling Operation

First, the air-cooling operation is described using FIG. 1.

During the air-cooling operation, the four-way switching valve 22 is in the state indicated by the solid lines in FIG. 1, i.e., a state in which the discharge side of the compressor 21 is connected to the gas side of the outdoor heat exchanger 23, and the intake side of the compressor 21 is connected to the gas sides of the indoor heat exchangers 42, 52, 62 via the gas-side shutoff valve 27 and the gas refrigerant communication tube 72. The outdoor expansion valve 38 is fully open at this time. The liquid-side shutoff valve 26 and the gas-side shutoff valve 27 are open. The opening degree of the indoor expansion valve 41 is adjusted so that the degree of superheat SH1 of the refrigerant in the outlet of the indoor heat exchanger 42 (i.e., the gas side of the indoor heat exchanger 42) reaches a target degree of superheat SHt1, the opening degree of the indoor expansion valve 51 is adjusted so that the degree of superheat SH2 of the refrigerant in the outlet of the indoor heat exchanger 52 (i.e., the gas side of the indoor heat exchanger 52) is constant at a target degree of superheat SHt2, and the opening degree of the indoor expansion valve 61 is adjusted so that the degree of superheat SH3 of the refrigerant in the outlet of the indoor heat exchanger 62 (i.e., the gas side of the indoor heat exchanger 62) reaches a target degree of superheat SHt3.

The target degrees of superheat SHt1, SHt2, SHt3 are set to the optimal temperature values in order for the indoor temperatures Tr1, Tr2, Tr3 to approach the set temperatures Ts1, Ts2, Ts3 within a predetermined degree of superheat range. The degrees of superheat SH1, SH2, SH3 of the refrigerant in the outlets of the indoor heat exchangers 42, 52, 62 are respectively detected by subtracting the refriger-

ant temperature values (corresponding to the evaporation temperature T_e) detected by the liquid line temperature sensors **44, 54, 64** from the refrigerant temperature values detected by the gas line temperature sensors **45, 55, 65**. The degrees of superheat SH_1, SH_2, SH_3 of the refrigerant in the outlets of the indoor heat exchangers **42, 52, 62** are not limited to being detected by the above method, and may be detected by converting the intake pressure of the compressor **21** detected by the intake pressure sensor **29** to a saturation temperature value corresponding to the evaporation temperature T_e , and subtracting this refrigerant saturation temperature value from the refrigerant temperature values detected by the gas line temperature sensors **45, 55, 65**.

Though not employed in the present embodiment, the degrees of superheat SH_1, SH_2, SH_3 of the refrigerant in the outlets of the indoor heat exchangers **42, 52, 62** may be detected by providing temperature sensors for detecting the temperatures of the refrigerant flowing within the indoor heat exchangers **42, 52, 62**, and subtracting the refrigerant temperature values corresponding to the evaporation temperatures T_e detected by these temperature sensors from the refrigerant temperature values detected by the gas line temperature sensors **45, 55, 65**.

When the compressor **21**, the outdoor fan **28**, and the indoor fans **43, 53, 63** are operated during this state of the refrigerant circuit **11**, low-pressure gas refrigerant is drawn into the compressor **21** and compressed to high-pressure gas refrigerant. The high-pressure gas refrigerant is then sent to the outdoor heat exchanger **23** via the four-way switching valve **22**, and the refrigerant exchanges heat with outdoor air supplied by the outdoor fan **28** and condenses to high-pressure liquid refrigerant. The high-pressure liquid refrigerant is sent to the indoor units **40, 50, 60** via the liquid-side shutoff valve **26** and the liquid refrigerant communication tube **71**.

The high-pressure liquid refrigerant sent to the indoor units **40, 50, 60** is pressure-reduced nearly to the intake pressure of the compressor **21** by the indoor expansion valves **41, 51, 61**, becoming low-pressure gas-liquid two-phase refrigerant which is sent to the indoor heat exchangers **42, 52, 62**, and the refrigerant exchanges heat with indoor air in the indoor heat exchangers **42, 52, 62** and evaporates to low-pressure gas refrigerant.

This low-pressure gas refrigerant is sent to the outdoor unit **20** via the gas refrigerant communication tube **72**, and the refrigerant flows through the gas-side shutoff valve **27** and the four-way switching valve **22** into the accumulator **24**. The low-pressure gas refrigerant that has flowed into the accumulator **24** is again drawn into the compressor **21**. An air-cooling operation can be performed in the air conditioning apparatus **10**, in which the outdoor heat exchanger **23** is made to function as a condenser of the refrigerant compressed in the compressor **21**, and the indoor heat exchangers **42, 52, 62** are made to function as evaporators of the refrigerant condensed in the outdoor heat exchanger **23** and then sent through the liquid refrigerant communication tube **71** and the indoor expansion valves **41, 51, 61**. In the air conditioning apparatus **10**, because the indoor units **40, 50, 60** have no mechanisms for adjusting the pressure of the refrigerant in the gas sides of the indoor heat exchangers **42, 52, 62**, the indoor heat exchangers **42, 52, 62** all share a common evaporation pressure P_e .

Energy conservation control is performed during this air-cooling operation in the air conditioning apparatus **10**. The energy conservation control during the air-cooling operation is described below on the basis of the flowchart of FIG. 3.

First, in step S11, the air-conditioning capability calculation units **47a, 57a, 67a** of the indoor-side control devices **47, 57, 67** of the indoor units **40, 50, 60** respectively calculate the air-conditioning capabilities **Q11, Q12, Q13** in the indoor units **40, 50, 60** on the basis of temperature differences $\Delta Ter_1, \Delta Ter_2, \Delta Ter_3$ which are the temperature differences between the indoor temperatures Tr_1, Tr_2, Tr_3 and the evaporation temperature T_e , indoor fan airflow volumes Ga_1, Ga_2, Ga_3 caused by the indoor fans **43, 53, 63**, and the degrees of superheat SH_1, SH_2, SH_3 , at that point in time. The calculated air-conditioning capabilities **Q11, Q12, Q13** are stored respectively in the memories **47c, 57c, 67c** of the indoor-side control devices **47, 57, 67**. The air-conditioning capabilities **Q11, Q12, Q13** may also be calculated using the evaporation temperature T_e instead of the temperature differences $\Delta Ter_1, \Delta Ter_2, \Delta Ter_3$.

In step S12, the air-conditioning capability calculation units **47a, 57a, 67a** respectively calculate displacements $\Delta Q_1, \Delta Q_2, \Delta Q_3$ of the air-conditioning capabilities in the indoor space on the basis of the indoor temperatures Tr_1, Tr_2, Tr_3 calculated respectively by the indoor temperature sensors **46, 56, 66**, and the temperature differences $\Delta T_1, \Delta T_2, \Delta T_3$ with the set temperatures Ts_1, Ts_2, Ts_3 set by a user through a remote controller or the like at the time. The air-conditioning capability calculation units **47a, 57a, 67a** then respectively calculate required capabilities **Q21, Q22, Q23** by adding the displacements to the air-conditioning capabilities **Q11, Q12, Q13**. The calculated required capabilities **Q21, Q22, Q23** are respectively stored in the memories **47c, 57c, 67c** of the indoor-side control devices **47, 57, 67**.

Though not shown in FIG. 3, when the indoor fans **43, 53, 63** are set to the automatic-airflow-volume-control mode in the indoor units **40, 50, 60** as described above, indoor temperature control is performed for adjusting the airflow volumes of the indoor fans **43, 53, 63** and the opening degrees of the indoor expansion valves **41, 51, 61** on the basis of the required capabilities **Q21, Q22, Q23**, so that the indoor temperatures Tr_1, Tr_2, Tr_3 respectively approach the set temperatures Ts_1, Ts_2, Ts_3 . When the indoor fans **43, 53, 63** are set to the constant-airflow-volume mode, indoor temperature control is performed for adjusting the opening degrees of the indoor expansion valves **41, 51, 61** on the basis of the required capabilities **Q21, Q22, Q23**, so that the indoor temperatures Tr_1, Tr_2, Tr_3 respectively approach the set temperatures Ts_1, Ts_2, Ts_3 .

Specifically, due to indoor temperature control, the air-conditioning capabilities of the indoor units **40, 50, 60** are maintained respectively between the above-described air-conditioning capabilities **Q11, Q12, Q13** and the required capabilities **Q21, Q22, Q23**. Essentially, the equivalent of the amount of heat exchanged in the indoor heat exchangers **42, 52, 62** is between the air-conditioning capabilities **Q11, Q12, Q13** of the indoor units **40, 50, 60** and the required capabilities **Q21, Q22, Q23**. Therefore, during energy conservation control when sufficient time has elapsed after the start of operation and a nearly steady state has been reached, the air-conditioning capabilities **Q11, Q12, Q13** of the indoor units **40, 50, 60** and/or the required capabilities **Q21, Q22, Q23** are nearly equivalent to the current amounts of heat exchanged in the indoor heat exchangers **42, 52, 62**.

In step S13, a confirmation is made as to whether the airflow-volume set mode in the remote controllers of the indoor fans **43, 53, 63** is the automatic-airflow-volume-control mode or the constant-airflow-volume mode. When the airflow-volume set mode of the indoor fans **43, 53, 63** is the automatic-airflow-volume-control mode, the sequence

transitions to step S14, and when the mode is the constant airflow-volume mode, the sequence transitions to step S15.

In step S14, the required temperature calculation units 47b, 57b, 67b respectively calculate required evaporation temperatures Ter1, Ter2, Ter3 of the indoor units 40, 50, 60 on the basis of the required capabilities Q21, Q22, Q23, airflow volume maximum values Ga_{MAX1} , Ga_{MAX2} , Ga_{MAX3} (the airflow volumes in "high airflow") of the indoor fans 43, 53, 63, and degree of superheat minimum values SH_{min1} , SH_{min2} , SH_{min3} . The required temperature calculation units 47b, 57b, 67b also respectively calculate evaporation temperature differences $\Delta Te1$, $\Delta Te2$, $\Delta Te3$, which are the required evaporation temperatures Ter1, Ter2, Ter3 less the evaporation temperatures $Te1$, $Te2$, $Te3$ detected by the liquid line temperature sensors 44, 54, 64 at the time. The term "degree of superheat minimum value SH_{min} " used herein refers to the minimum value of the range in which the degree of superheat can be set by adjusting the opening degrees of the indoor expansion valves 41, 51, 61, the respective values SH_{min1} , SH_{min2} , SH_{min3} are set according to the model, and the set values are sometimes different from each other and sometimes the same as each other. In the indoor units 40, 50, 60, when the airflow volumes of the indoor fans 43, 53, 63 and/or the degrees of superheat are brought to the airflow volume maximum values Ga_{MAX1} , Ga_{MAX2} , Ga_{MAX3} and the degree of superheat minimum values SH_{min1} , SH_{min2} , SH_{min3} , if they are not currently at the airflow volume maximum values Ga_{MAX1} , Ga_{MAX2} , Ga_{MAX3} and the degree of superheat minimum values SH_{min1} , SH_{min2} , SH_{min3} , it is possible to create a state in which greater amounts of heat exchanged than the current amounts are exhibited in the indoor heat exchangers 42, 52, 62. Therefore, an operating state amount involving the airflow volume maximum values Ga_{MAX1} , Ga_{MAX2} , Ga_{MAX3} and the degree of superheat minimum values SH_{min1} , SH_{min2} , SH_{min3} is an operating state amount that can create a state in which greater amounts of heat exchanged than the current amounts are exhibited in the indoor heat exchangers 42, 52, 62. The calculated evaporation temperature differences $\Delta Te1$, $\Delta Te2$, $\Delta Te3$ are then stored respectively in the memories 47c, 57c, 67c of the indoor-side control devices 47, 57, 67.

In step S15, the required temperature calculation units 47b, 57b, 67b respectively calculate the required evaporation temperatures Ter1, Ter2, Ter3 of the indoor units 40, 50, 60 on the basis of the required capabilities Q21, Q22, Q23, the constant airflow volumes $Ga1$, $Ga2$, $Ga3$ (e.g., the airflow volumes in "medium airflow") of the indoor fans 43, 53, 63, and the degree of superheat minimum values SH_{min1} , SH_{min2} , SH_{min3} . The required temperature calculation units 47b, 57b, 67b also respectively calculate the evaporation temperature differences $\Delta Te1$, $\Delta Te2$, $\Delta Te3$, which are the required evaporation temperatures Ter1, Ter2, Ter3 less the evaporation temperature Te detected by the liquid line temperature sensors 44, 54, 64 at the time. The calculated evaporation temperature differences $\Delta Te1$, $\Delta Te2$, $\Delta Te3$ are stored respectively in the memories 47c, 57c, 67c of the indoor-side control devices 47, 57, 67. In this step S15, the constant airflow volumes $Ga1$, $Ga2$, $Ga3$ are employed instead of the airflow volume maximum values Ga_{MAX1} , Ga_{MAX2} , Ga_{MAX3} , but the purpose of this is to prioritize the airflow volumes set by the user, and the airflow volumes will be recognized as airflow volume maximum values within the range set by the user.

In step S16, the evaporation temperature differences $\Delta Te1$, $\Delta Te2$, $\Delta Te3$, which had been stored respectively in the memories 47c, 57c, 67c of the indoor-side control devices

47, 57, 67 in steps S14 and S15, are sent to the outdoor-side control device 37 and stored in the memory 37b of the outdoor-side control device 37. The target value appointing unit 37a of the outdoor-side control device 37 then appoints a minimum evaporation temperature difference ΔTe_{min} , which is the minimum among the evaporation temperature differences $\Delta Te1$, $\Delta Te2$, $\Delta Te3$, as the target evaporation temperature difference ΔTet . For example, when the evaporation temperature differences $\Delta Te1$, $\Delta Te2$, $\Delta Te3$ of the indoor units 40, 50, 60 are 1° C., 0° C., and -2° C., the ΔTe_{min} is -2° C.

In step S17, the operating capacity of the compressor 21 is controlled so that the evaporation temperature nears the new target evaporation temperature Tet updated with the ΔTe_{min} . Thus, as a result of the operating capacity of the compressor 21 being controlled on the basis of the target evaporation temperature difference ΔTet , in the indoor unit (assume the indoor unit 40 in this case) that had calculated the minimum evaporation temperature difference ΔTe_{min} employed as the target evaporation temperature difference ΔTet , the indoor fan 43 is adjusted so as to reach the airflow volume maximum value Ga_{MAX1} when set to the automatic-airflow-volume-control mode, and the indoor expansion valve 41 is adjusted so that the degree of superheat SH in the outlet of the indoor heat exchanger 42 reaches the degree of superheat minimum value SH_{min1} .

Air-cooling heat exchange functions, which differ for each of the indoor units 40, 50, 60 and take into account the relationships of the air-conditioning (required) capabilities Q11, Q12, Q13 (Q21, Q22, Q23), airflow volumes $Ga1$, $Ga2$, $Ga3$, degrees of superheat $SH1$, $SH2$, $SH3$, and temperature differences $\Delta Ter1$, $\Delta Ter2$, $\Delta Ter3$ of each of the indoor units 40, 50, 60, are used to calculate the air-conditioning capabilities Q11, Q12, Q13 in step S11 and to calculate the evaporation temperature differences $\Delta Te1$, $\Delta Te2$, $\Delta Te3$ in step S14 or S15. These air-cooling heat exchange functions are relational expressions associated with the air-conditioning (required) capabilities Q11, Q12, Q13 (Q21, Q22, Q23), airflow volumes $Ga1$, $Ga2$, $Ga3$, degrees of superheat $SH1$, $SH2$, $SH3$, and temperature differences $\Delta Ter1$, $\Delta Ter2$, $\Delta Ter3$ representing the characteristics of the indoor heat exchangers 42, 52, 62, and these functions are stored respectively in the memories 47c, 57c, 67c of the indoor-side control devices 47, 57, 67 of the indoor units 40, 50, 60. One variable among the air-conditioning (required) capabilities Q11, Q12, Q13 (Q21, Q22, Q23), airflow volumes $Ga1$, $Ga2$, $Ga3$, degrees of superheat $SH1$, $SH2$, $SH3$, and temperature differences $\Delta Ter1$, $\Delta Ter2$, $\Delta Ter3$ is determined by inputting the other three variables into the air-cooling heat exchange functions. The evaporation temperature differences $\Delta Te1$, $\Delta Te2$, $\Delta Te3$ can thereby be brought to the proper values with precision, and the target evaporation temperature difference ΔTet can be accurately determined. Therefore, excessive increases of the evaporation temperature Te can be prevented. Therefore, excess and deficiency in the air-conditioning capabilities of the indoor units 40, 50, 60 can be prevented, the optimal states of the indoor units 40, 50, 60 can be achieved quickly and stably, and a greater energy conservation effect can be exhibited.

The target evaporation temperature let is updated on the basis of the target evaporation temperature difference ΔTet in this flow to control the operating capacity of the compressor 21, but the target evaporation temperature is not limited to the target evaporation temperature difference ΔTet , the target value appointing unit 37a may appoint the minimum value of the required evaporation temperature Ter calculated in the indoor units 40, 50, 60 as the target

evaporation temperature T_{et} , and the operating capacity of the compressor **21** may be controlled on the basis of the appointed target evaporation temperature T_{et} .

(2-2) Air-Heating Operation

Next, the air-heating operation is described using FIG. 1.

During the air-heating operation, the four-way switching valve **22** is in the state indicated by the dashed lines in FIG. 1 (the air-heating operation state), i.e., a state in which the discharge side of the compressor **21** is connected to the gas sides of the indoor heat exchangers **42, 52, 62** via the gas-side shutoff valve **27** and the gas refrigerant communication tube **72**, and the intake side of the compressor **21** is connected to the gas side of the outdoor heat exchanger **23**. The opening degree of the outdoor expansion valve **38** is adjusted in order to depressurize the refrigerant flowing into the outdoor heat exchanger **23** to a pressure at which the refrigerant can be evaporated (i.e., the evaporation pressure P_e) in the outdoor heat exchanger **23**. The liquid-side shutoff valve **26** and the gas-side shutoff valve **27** are open. The opening degrees of the indoor expansion valves **41, 51, 61** are adjusted so that the degrees of subcooling **SC1, SC2, SC3** of the refrigerant in the outlets of the indoor heat exchangers **42, 52, 62** respectively reach target degrees of subcooling **SCt1, SCt2, SCt3**. The target degrees of subcooling **SCt1, SCt2, SCt3** are set to optimal temperature values in order for the indoor temperatures Tr_1, Tr_2, Tr_3 to approach the set temperatures Ts_1, Ts_2, Ts_3 within the degree of subcooling range specified according to the operating state at that time. The degrees of subcooling **SC1, SC2, SC3** of the refrigerant in the outlets of the indoor heat exchangers **42, 52, 62** are detected by converting the discharge pressure P_d of the compressor **21** detected by the discharge pressure sensor **30** to a saturation temperature value corresponding to the condensation temperature T_c , and subtracting the refrigerant temperature values detected by the liquid line temperature sensors **44, 54, 64** from this refrigerant saturation temperature value.

Though not employed in the present embodiment, temperature sensors may be provided for detecting the temperature of the refrigerant flowing within the indoor heat exchangers **42, 52, 62**, and the degrees of subcooling **SC1, SC2, SC3** of the refrigerant in the outlets of the indoor heat exchangers **42, 52, 62** may be detected by subtracting the refrigerant temperature values corresponding to the condensation temperature T_c detected by these temperature sensors from the refrigerant temperature values detected by the liquid line temperature sensors **44, 54, 64**.

When the compressor **21**, the outdoor fan **28**, and the indoor fans **43, 53, 63** are operated in this state of the refrigerant circuit **11**, low-pressure gas refrigerant is drawn into the compressor **21** and compressed to high-pressure gas refrigerant, which is sent to the indoor units **40, 50, 60** via the four-way switching valve **22**, the gas-side shutoff valve **27**, and the gas refrigerant communication tube **72**.

The high-pressure gas refrigerant sent to the indoor units **40, 50, 60** exchanges heat with indoor air in the indoor heat exchangers **42, 52, 62** and condenses to high-pressure liquid refrigerant, which then passes through the indoor expansion valves **41, 51, 61** to be pressure-reduced in accordance with the valve opening degrees of the indoor expansion valves **41, 51, 61**.

The refrigerant that has passed through the indoor expansion valves **41, 51, 61** is sent to the outdoor unit **20** via the liquid refrigerant communication tube **71** and further pressure-reduced via the liquid-side shutoff valve **26** and the outdoor expansion valve **38**, after which the refrigerant flows into the outdoor heat exchanger **23**. The low-pressure

gas-liquid two-phase refrigerant that has flowed into the outdoor heat exchanger **23** exchanges heat with outdoor air supplied by the outdoor fan **28** and evaporates to low-pressure gas refrigerant, which flows into the accumulator **24** via the four-way switching valve **22**. The low-pressure gas refrigerant that has flowed into the accumulator **24** is again drawn into the compressor **21**. Because the air conditioning apparatus **10** has no mechanisms for adjusting the pressure of the refrigerant in the gas sides of the indoor heat exchangers **42, 52, 62**, the indoor heat exchangers **42, 52, 62** all share a common condensation pressure P_c .

Energy conservation control is performed during the air-heating operation in the air conditioning apparatus **10**. The energy conservation control during the air-heating operation is described below on the basis of the flowchart of FIG. 4.

First, in step S21, the air-conditioning capability calculation units **47a, 57a, 67a** of the indoor-side control devices **47, 57, 67** of the indoor units **40, 50, 60** respectively calculate the current air-conditioning capabilities **Q31, Q32, Q33** in the indoor units **40, 50, 60** on the basis of temperature differences $\Delta T_{cr1}, \Delta T_{cr2}, \Delta T_{cr3}$ which are the temperature differences between the indoor temperatures Tr_1, Tr_2, Tr_3 and the condensation temperature T_c , indoor fan airflow volumes Ga_1, Ga_2, Ga_3 caused by the indoor fans **43, 53, 63**, and the degrees of subcooling **SC1, SC2, SC3**, at that point in time. The calculated air-conditioning capabilities **Q31, Q32, Q33** are stored respectively in the memories **47c, 57c, 67c** of the indoor-side control devices **47, 57, 67**. The air-conditioning capabilities **Q31, Q32, Q33** may also be calculated using the condensation temperature T_c instead of the temperature differences $\Delta T_{cr1}, \Delta T_{cr2}, \Delta T_{cr3}$.

In step S22, the air-conditioning capability calculation units **47a, 57a, 67a** respectively calculate displacements $\Delta Q_1, \Delta Q_2, \Delta Q_3$ of the air-conditioning capabilities in the indoor space on the basis of the indoor temperatures Tr_1, Tr_2, Tr_3 detected respectively by the indoor temperature sensors **46, 56, 66**, and the temperature differences $\Delta T_1, \Delta T_2, \Delta T_3$ with the set temperatures Ts_1, Ts_2, Ts_3 set by a user through a remote controller or the like at the time. The air-conditioning capability calculation units **47a, 57a, 67a** then respectively calculate required capabilities **Q41, Q42, Q43** by adding the displacements to the air-conditioning capabilities **Q31, Q32, Q33**. The calculated required capabilities **Q41, Q42, Q43** are respectively stored in the memories **47c, 57c, 67c** of the indoor-side control devices **47, 57, 67**. Though not shown in FIG. 4, when the indoor fans **43, 53, 63** are set to the automatic-airflow-volume-control mode in the indoor units **40, 50, 60** as described above, indoor temperature control is performed for adjusting the airflow volumes of the indoor fans **43, 53, 63** and the opening degrees of the indoor expansion valves **41, 51, 61** on the basis of the required capabilities **Q41, Q42, Q43**, so that the indoor temperatures Tr_1, Tr_2, Tr_3 respectively approach the set temperatures Ts_1, Ts_2, Ts_3 . When the indoor fans **43, 53, 63** are set to the constant-airflow-volume mode, indoor temperature control is performed for adjusting the opening degrees of the indoor expansion valves **41, 51, 61** on the basis of the required capabilities **Q41, Q42, Q43**, so that the indoor temperatures Tr_1, Tr_2, Tr_3 respectively approach the set temperatures Ts_1, Ts_2, Ts_3 .

Specifically, due to indoor temperature control, the air-conditioning capabilities of the indoor units **40, 50, 60** continue to be maintained respectively between the above-described air-conditioning capabilities **Q31, Q32, Q33** and the required capabilities **Q41, Q42, Q43**. Essentially, the amount of heat exchanged in the indoor heat exchangers **42,**

52, 62 is between the air-conditioning capabilities Q31, Q32, Q33 of the indoor units 40, 50, 60 and the required capabilities Q41, Q42, Q43. Therefore, during energy conservation control when sufficient time has elapsed after the start of operation and a nearly steady state has been reached, the air-conditioning capabilities Q31, Q32, Q33 of the indoor units 40, 50, 60 and/or the required capabilities Q41, Q42, Q43 are nearly equivalent to the current amounts of heat exchanged in the indoor heat exchangers 42, 52, 62.

In step S23, a confirmation is made as to whether the airflow-volume set mode in the remote controllers of the indoor fans 43, 53, 63 is the automatic-airflow-volume-control mode or the constant-airflow-volume mode. When the airflow-volume set mode of the indoor fans 43, 53, 63 is the automatic-airflow-volume-control mode, the sequence transitions to step S24, and when the mode is the constant-airflow-volume mode, the sequence transitions to step S25.

In step S24, the required temperature calculation units 47b, 57b, 67b respectively calculate required condensation temperatures Tcr1, Tcr2, Tcr3 of the indoor units 40, 50, 60 on the basis of the required capabilities Q41, Q42, Q43, the airflow volume maximum values Ga_{MAX1}, Ga_{MAX2}, Ga_{MAX3} (the airflow volumes in "high airflow") of the indoor fans 43, 53, 63, and degree of subcooling minimum values SC_{min1}, SC_{min2}, SC_{min3}. The required temperature calculation units 47b, 57b, 67b also respectively calculate condensation temperature differences $\Delta Tc1$, $\Delta Tc2$, $\Delta Tc3$, which are the required condensation temperatures Tcr1, Tcr2, Tcr3 less the condensation temperatures Tc1, Tc2, Tc3 detected by the liquid line temperature sensors 44, 54, 64 at the time. The term "degree of subcooling minimum value SC_{min}" used herein refers to the minimum value of the range in which the degree of subcooling can be set by adjusting the opening degrees of the indoor expansion valves 41, 51, 61, and the respective values SC_{min1}, SC_{min2}, SC_{min3} are set according to the model. In the indoor units 40, 50, 60, when the airflow volumes of the indoor fans 43, 53, 63 and/or the degrees of subcooling are brought to the airflow volume maximum values Ga_{MAX1}, Ga_{MAX2}, Ga_{MAX3} and the degree of subcooling minimum values SC_{min1}, SC_{min2}, SC_{min3}, if they are not currently at the airflow volume maximum values Ga_{MAX1}, Ga_{MAX2}, Ga_{MAX3} and the degree of subcooling minimum values SC_{min1}, SC_{min2}, SC_{min3}, it is possible to create a state in which greater amounts of heat exchanged than the current amounts are exhibited in the indoor heat exchangers 42, 52, 62. Therefore, an operating state amount involving the airflow volume maximum values Ga_{MAX1}, Ga_{MAX2}, Ga_{MAX3} and the degree of subcooling minimum values SC_{min1}, SC_{min2}, SC_{min3} is an operating state amount that can create a state in which greater amounts of heat exchanged than the current amounts are exhibited in the indoor heat exchangers 42, 52, 62. The calculated condensation temperature differences $\Delta Tc1$, $\Delta Tc2$, $\Delta Tc3$ are then stored respectively in the memories 47c, 57c, 67c of the indoor-side control devices 47, 57, 67.

In step S25, the required temperature calculation units 47b, 57b, 67b respectively calculate the required condensation temperatures Tcr1, Tcr2, Tcr3 of the indoor units 40, 50, 60 on the basis of the required capabilities Q41, Q42, Q43, the constant airflow volumes Ga1, Ga2, Ga3 (e.g., the airflow volumes in "medium airflow") of the indoor fans 43, 53, 63, and the degree of subcooling minimum values SC_{min1}, SC_{min2}, SC_{min3}. The required temperature calculation units 47b, 57b, 67b also respectively calculate the condensation temperature differences $\Delta Tc1$, $\Delta Tc2$, $\Delta Tc3$, which are the required condensation temperatures Tcr1, Tcr2, Tcr3 less the condensation temperatures Tc1, Tc2, Tc3

detected by the liquid line temperature sensors 44, 54, 64 at the time. The calculated condensation temperature differences $\Delta Tc1$, $\Delta Tc2$, $\Delta Tc3$ are stored respectively in the memories 47c, 57c, 67c of the indoor-side control devices 47, 57, 67. In this step S25, the constant airflow volumes Ga1, Ga2, Ga3 are employed instead of the airflow volume maximum values Ga_{MAX1}, Ga_{MAX2}, Ga_{MAX3}, but the purpose of this is to prioritize the airflow volumes set by the user, and the airflow volumes will be recognized as maximum values within the airflow volume range set by the user.

In step S26, the condensation temperature differences $\Delta Tc1$, $\Delta Tc2$, $\Delta Tc3$, which had been stored respectively in the memories 47c, 57c, 67c of the indoor-side control devices 47, 57, 67 in steps S24 and S25, are sent to the outdoor-side control device 37 and stored in the memory 37b of the outdoor-side control device 37. The target value appointing unit 37a of the outdoor-side control device 37 then appoints a maximum condensation temperature difference ΔTc_{max} , which is the maximum among the condensation temperature differences $\Delta Tc1$, $\Delta Tc2$, $\Delta Tc3$, as the target condensation temperature difference ΔTct . For example, when the condensation temperature differences $\Delta Tc1$, $\Delta Tc2$, $\Delta Tc3$ of the indoor units 40, 50, 60 are 1° C., 0° C., and -2° C., the ΔTc_{max} is 1° C.

In step S27, the operating capacity of the compressor 21 is controlled on the basis of the target condensation temperature difference ΔTct . Thus, as a result of the operating capacity of the compressor 21 being controlled on the basis of the target condensation temperature difference ΔTct , in the indoor unit (assume the indoor unit 40 in this case) that had calculated the maximum condensation temperature difference ΔTc_{max} employed as the target condensation temperature difference ΔTct , the indoor fan 43 is adjusted so as to reach the airflow volume maximum value Ga_{MAX1} when set to the automatic-airflow-volume-control mode, and the indoor expansion valve 41 is adjusted so that the degree of subcooling SC in the outlet of the indoor heat exchanger 42 reaches the degree of subcooling minimum value SC_{min1}.

Air-heating heat exchange functions, which differ for each of the indoor units 40, 50, 60 and take into account the relationships of the air-conditioning (required) capabilities Q31, Q32, Q33 (Q41, Q42, Q43), airflow volumes Ga1, Ga2, Ga3, degrees of subcooling SC1, SC2, SC3, and temperature differences $\Delta Tcr1$, $\Delta Tcr2$, $\Delta Tcr3$ (the temperature difference between the indoor temperature Tr and the condensation temperature Tc) of each of the indoor units 40, 50, 60, are used to calculate the air-conditioning capabilities Q31, Q32, Q33 in step S21 and to calculate the condensation temperature differences $\Delta Tc1$, $\Delta Tc2$, $\Delta Tc3$ in step S24 or S25. These air-heating heat exchange functions are relational expressions associated with the air-conditioning (required) capabilities Q31, Q32, Q33 (Q41, Q42, Q43), airflow volumes Ga1, Ga2, Ga3, degrees of subcooling SC1, SC2, SC3, and temperature differences $\Delta Tcr1$, $\Delta Tcr2$, $\Delta Tcr3$ representing the characteristics of the indoor heat exchangers 42, 52, 62, and these functions are stored respectively in the memories 47c, 57c, 67c of the indoor-side control devices 47, 57, 67 of the indoor units 40, 50, 60. One variable among the air-conditioning (required) capabilities Q31, Q32, Q33 (Q41, Q42, Q43), airflow volumes Ga1, Ga2, Ga3, degrees of subcooling SC1, SC2, SC3, and temperature differences $\Delta Tcr1$, $\Delta Tcr2$, $\Delta Tcr3$ is determined respectively by inputting the other three variables into the air-heating heat exchange functions. The condensation temperature differences $\Delta Tc1$, $\Delta Tc2$, $\Delta Tc3$ can thereby be brought to the proper values with precision, and the target condensation temperature difference ΔTct can be accurately

determined. Therefore, excessive increases of the condensation temperature T_c can be prevented. Therefore, excess and deficiency in the air-conditioning capabilities of the indoor units **40, 50, 60** can be prevented, the optimal states of the indoor units **40, 50, 60** can be achieved quickly and stably, and a greater energy conservation effect can be exhibited.

The operating capacity of the compressor **21** is controlled on the basis of the target condensation temperature difference ΔT_{ct} in this flow, but this control is not limited to the target condensation temperature difference ΔT_{ct} , the target value appointing unit **37a** may appoint the maximum value of the requested condensation temperature T_{cr} calculated in the indoor units **40, 50, 60** as the target condensation temperature T_{ct} , and the operating capacity of the compressor **21** may be controlled on the basis of the appointed target condensation temperature T_{ct} .

The operation controls described above are performed by the operation control device **80** (more specifically, the indoor-side control devices **47, 57, 67**, the outdoor-side control device **37**, and the transmission line **80a** connecting them) which functions as operation control means for performing normal operations including the air-cooling operation and the air-heating operation.

(2-3) Equalizing Indoor Unit Operating States

Next, FIG. 5 is used to describe equalizing the indoor unit operating states, in which a transition is made from an unbalanced state in which some indoor units within the same group of indoor units are thermo-ON, to a state in which more indoor units are thermo-ON.

For this description, the indoor units **40, 50, 60** are designated as a single group AA. The indoor-side control devices **47, 57, 67** have the information that the respective indoor units **40, 50, 60** belong to group AA. The indoor units **40, 50, 60** obtain information pertaining to the groups of other indoor units (step S31), whereby the indoor units **40, 50, 60** perform a grouping indicating that the units belong to the same group AA. The indoor-side control devices **47, 57, 67** then obtain information indicating whether the indoor units **40, 50, 60** belonging to the same group AA are thermo-ON or thermo-OFF (step S32).

Next, an assessment made among the indoor units **40, 50, 60** as to whether all of the indoor units **40, 50, 60** belonging to group AA are thermo-ON, all are thermo-OFF, or there are both thermo-ON indoor units and thermo-OFF indoor units (step S33).

When it is assessed in step S33 that all three of the indoor units **40, 50, 60** in group AA are thermo-ON, the indoor-side control devices **47, 57, 67** recognize that there is no need to resolve there are both thermo-ON and thermo-OFF units. In view of this, the indoor units **40, 50, 60** return to step S32 and again obtain the information indicating whether the indoor units **40, 50, 60** are thermo-ON or thermo-OFF with the following timing. The operation of step S33 onward is then performed.

When it is assessed in step S33 that all three of the indoor units **40, 50, 60** in group AA are thermo-OFF, the indoor-side control devices **47, 57, 67** recognize that there is no need to resolve there are both thermo-ON and thermo-OFF units. However, at this time, there are both cases in which all three units in group AA are set to the thermo-ON differential of the initial state, and cases in which the thermo-ON differential of some indoor units is reduced from the initial state by the operation of step S35, described hereinafter. The thermo-ON differential is the temperature difference between the set temperature and the temperature at which an indoor unit in the thermo-OFF state is switched thermo-ON.

In view of this, in order to return the thermo-ON differential to the initial state in an indoor unit of which the thermo-ON differential has been reduced from the initial state, the thermo-ON differentials of the indoor units **40, 50, 60** in group AA are reset (step S36). The indoor units **40, 50, 60** then return to step S32 and again obtain the information indicating whether the indoor units **40, 50, 60** are thermo-ON or thermo-OFF. The operation of step S33 onward is then performed.

When it is assessed in step S33 that some of the three indoor units **40, 50, 60** in group AA are thermo-OFF, the indoor-side control devices **47, 57, 67** of the indoor units **40, 50, 60** all recognize that there are both thermo-ON and thermo-OFF units. Therefore, the indoor-side control devices **47, 57, 67** of the indoor units **40, 50, 60** advance to the next step S34, and from the thermo-ON and thermo-OFF information stored in the memories **47c, 57c, 67c** of the indoor-side control devices **47, 57, 67**, the control devices assess whether or not there are indoor units within group AA that have continued to be thermo-ON for ten minutes or longer, and also indoor units within group AA that have continued to be thermo-OFF for ten minutes or longer. In this step S34, a continuation of ten minutes is assessed, but the continuation time is set as appropriate. For example, when the indoor unit **40** has continued to be thermo-ON for ten minutes or longer and the indoor units **50, 60** have continued to be thermo-OFF for ten minutes or longer, the assessment condition of step S34 is satisfied, and the sequence therefore advances to the next step S35. As another example, when the indoor unit **40** has continued to be thermo-ON for ten minutes or longer but the indoor units **50, 60** have repeated thermo-ON and thermo-OFF and have only continued thermo-OFF for less than ten minutes, the assessment condition of step S34, is not satisfied, the sequence therefore returns to step S32, and the operation of step S32 onward is repeated.

In step S35, an operation is performed for reducing the thermo-ON differential by $0.2^\circ C$. in indoor units continuing to be thermo-OFF. The differentially is provisionally reduced by $0.2^\circ C$. in this step S35, but the value by which the reduction is made is set as appropriate. In the example described above, the thermo-ON differentials of the indoor units **40, 50, 60** are reduced by $0.2^\circ C$. because the indoor units **50, 60** have continued to be thermo-OFF for ten minutes or longer. In another case, the thermo-ON differentials of the indoor units **40, 50, 60** are reduced by $0^\circ C$. even when, e.g., the indoor unit **50** has continued to be thermo-OFF for ten minutes or longer but the time duration of the indoor unit **60** being thermo-OFF is less than ten minutes. After the operation of this step S35, the sequence returns to step S32 and the operation of step S32 onward is repeated.

FIG. 6 is a graph showing an example of a case in which the indoor units **40, 50, 60** are controlled by the procedure shown in FIG. 5. In FIG. 6, the curve C1 represents the control temperature of the indoor unit **40** (the temperature detected by the indoor temperature sensor **46**), the curve C2 represents the control temperature of the indoor unit **50** (the temperature detected by the indoor temperature sensor **56**), and the curve C3 represents the control temperature of the indoor unit **60** (the temperature detected by the indoor temperature sensor **66**). In FIG. 6, the arrow Ar1 indicates the time period during which the indoor unit **40** is thermo-ON, the arrow Ar2 indicates the time period during which the indoor unit **50** is thermo-OFF, the arrow Ar3 indicates the time period during which the indoor unit **50** is thermo-ON, the arrow Ar4 indicates the time period during which

21

the indoor unit **60** is thermo-OFF, and the arrow Ar5 indicates the time period during which the indoor unit **60** is thermo-ON.

At time **t0** shown in FIG. 6, the indoor unit **40** is thermo-ON, but the indoor units **50**, **60** are thermo-OFF. Assuming the duration from time **t0** to time **t1** is ten minutes, the thermo-ON indoor unit **40** does not continue to be thermo-ON for ten minutes or longer up to time **t1**, and the operation from step S32 to step S34 is therefore repeated. At time **t1**, the indoor unit **40** has been thermo-ON for ten minutes or longer and the indoor units **50**, **60** have been thermo-OFF for ten minutes or longer, the sequence therefore advances to step S35, and the thermo-ON differentials of the indoor units **40**, **50**, **60** are reduced by 0.2°C . This process is carried out by, e.g., rewriting the thermo-ON differential values stored in the memories **47c**, **57c**, **67c** in the indoor-side control devices **47**, **57**, **67** of the indoor units **40**, **50**, **60**.

Due to the thermo-ON differentials decreasing at time **t1**, the temperature difference between curve C2 and the set value setting temperature is greater than the thermo-ON differentials after the decrease, and the indoor unit **50** is therefore thermo-ON.

The time duration between time **t1** and time **t2** is an interval following time **t1** and lasting until the procedure of step S32 onward is performed. At time **t2**, there are both thermo-ON indoor units **40**, **50** and a thermo-OFF indoor unit **60**, the sequence therefore advances to step S35, and the thermo-ON differentials of the indoor units **40**, **50**, **60** are further reduced by 0.2°C . As a result, due to the thermo-ON differentials decreasing at time **t2**, the temperature difference between curve C3 and the set value setting temperature is greater than the thermo-ON differentials after the decrease, and the indoor unit **60** is therefore thermo-ON.

(3) Characteristics

(3-1)

As described above, the indoor units **40**, **50**, **60** of the air conditioning apparatus **10** are installed in one room **1** (an example of the same indoor space). The indoor units **40**, **50**, **60** include respective indoor heat exchangers **42**, **52**, **62** (an example of the usage-side heat exchangers), and the indoor units are configured to be capable of setting the set temperatures individually. The indoor-side control devices **47**, **57**, **67** (an example of the control devices) cause temperature control of the room **1** to be performed in each of the indoor units **40**, **50**, **60**, using a thermo-ON condition set in advance in accordance with the set temperature. When the indoor units **40**, **50**, **60** include both those that are thermo-ON and those that are thermo-OFF and a predetermined condition is satisfied, the indoor-side control devices **47**, **57**, **67** reduce the thermo-ON differentials of the indoor units **40**, **50**, **60** that are thermo-OFF (an example of relaxing the thermo-ON condition).

At times **t1** and **t2** at which there are both thermo-ON units and thermo-OFF units among the three indoor units **40**, **50**, **60**, the thermo-ON condition is relaxed, whereby the number of thermo-ON indoor units can be quickly increased from one to two and also from two to three to increase the number of indoor heat exchangers **42**, **52**, **62** that are exchanging heat with the refrigerant circulating in the outdoor heat exchanger **23** (an example of the heat-source-side heat exchanger). As a result, there are more indoor units **40**, **50**, **60** that are thermo-ON, whereby heat exchange can be balanced with the apparent area of all the indoor heat exchangers **42**, **52**, **62** together (the sum of the area of the thermo-ON indoor heat exchangers **42**, **52**, **62**) having increased, and the differential pressure between the evapo-

22

ration pressure and the condensation pressure of the air conditioning system can be reduced to improve the efficiency of the entire air conditioning system.

The predetermined condition for the indoor-side control devices **47**, **57**, **67** is that among the indoor units **40**, **50**, **60** there are units that have continued to be thermo-ON for ten minutes (an example of the first elapsed time) or longer, and there are also units that have continued to be thermo-OFF for ten minutes (an example of the second elapsed time) or longer. It is possible to prevent a relaxing of the thermo-ON condition due to a temporary state in which indoor units that should be thermo-ON have continued to not be thermo-ON for ten minutes, or a temporary state in which indoor units that should be thermo-OFF have continued to not be thermo-OFF for ten minutes. Due to the control being configured in this manner, efficiency can be improved while imbalance of the temperature in the same indoor space is suppressed.

In the method for controlling the air conditioning system shown in FIG. 5, the state up to step S34 is an example of the first step of causing temperature control of the same indoor space to be performed in each of the indoor units **40**, **50**, **60**, using a thermo-ON condition set in advance in accordance with the set temperatures. Step S35 is an example of the second step of relaxing the thermo-ON condition of thermo-OFF indoor units when the indoor units **40**, **50**, **60** include both those that are thermo-ON and those that are thermo-OFF and a predetermined condition is satisfied.

(3-2)

As shown in FIG. 6, at times **t1** and **t2**, the indoor-side control devices **47**, **57**, **67** reduce the thermo-ON differentials without raising the thermo-OFF differentials (an example of not altering the thermo-OFF condition). Because the thermo-OFF differentials are not altered even though the thermo-ON differentials are reduced, thermo-OFF can be carried out at different timings depending on the set temperatures that are set in each of the indoor units **40**, **50**, **60**, and efficiency can be improved while carrying out operations conforming to the requirements of each of the indoor units **40**, **50**, **60**.

(3-3)

The indoor-side control devices **47**, **57**, **67** of the operation control device **80**, through the required temperature calculation units **47b**, **57b**, **67b**, calculate, each indoor unit, the required evaporation temperatures or the required condensation temperatures of the indoor heat exchangers **42**, **52**, **62**. The outdoor-side control device **37** of the operation control device **80** appoints a target evaporation temperature on the basis of the minimum value among the required evaporation temperatures of the indoor units **40**, **50**, **60** calculated in the required temperature calculation units **47b**, **57b**, **67b**. Alternatively, the outdoor-side control device **37** of the operation control device **80**, through the target value appointing unit **37a**, appoints a target condensation temperature on the basis of the maximum value among the required condensation temperatures of the indoor units **40**, **50**, **60** calculated in the required temperature calculation units **47b**, **57b**, **67b**. A target evaporation temperature or a target condensation temperature is thereby appointed for the outdoor unit **20** in response to the highest requirement of air-conditioning capability from among the indoor units **40**, **50**, **60**, whereby a target evaporation temperature or target condensation temperature complying with the air-conditioning capability requirements of all the indoor units **40**, **50**, **60** can be appointed and efficiency can be improved while preventing deficiencies in air-conditioning capability in some indoor units.

(3-4)

Because the indoor-side control device **47** of the indoor unit **40**, which is the base unit described above, uses the above formulas (1) and (2), rated capacities (an example of the degree of influence on the thermal environment of the indoor space) are derived from the differences between the set temperatures and the detected temperatures (an example of the control temperatures) of the respective indoor temperature sensors **46**, **56**, **66** of the indoor units **40**, **50**, **60**. In other words, a weighted average value, which is weighted by the rated capacities, is used as the representative temperature related value. Emphasis can thereby be placed on the indoor unit that has the greatest rated capacity and the greatest degree of influence on the thermal environment of the indoor space, and the degree of influence of each of the indoor units **40**, **50**, **60** on the indoor environment can be reflected.

(3-5)

The thermo-ON condition is a condition that the indoor units **40**, **50**, **60** be thermo-ON when there is a predetermined temperature difference (the thermo-ON differential) between the set temperature and the temperatures detected by the indoor temperature sensors **46**, **56**, **66** (an example of the control temperatures), and the indoor-side control devices relax the thermo-ON condition by reducing the thermo-ON differential (an example of reducing the predetermined temperature difference of the thermo-ON condition). Relaxing of the thermo-ON condition can thus be achieved by a simple operation of altering the thermo-ON differential, and control of an air conditioning system that readily turns thermo-ON can be achieved in a simple manner.

(3-6)

The indoor units **40**, **50**, **60** comprise respective indoor fans **43**, **53**, **63** (an example of the air blowers) of which the airflow volumes sent to the indoor heat exchangers **42**, **52**, **62** can be adjusted. The indoor-side control devices **47**, **57**, **67** adjust the indoor fans **43**, **53**, **63** for each indoor unit, reduce the airflow volumes if the air-conditioning capabilities are excessive, and increase the airflow volumes if the air-conditioning capabilities are insufficient. Through this manner of control, the indoor-side control devices **47**, **57**, **67** can autonomously adjust the air-conditioning capability of each indoor unit via the airflow volumes of the indoor fans **43**, **53**, **63**, and can autonomously optimize the air-conditioning capability. The number of thermo-ON indoor units is increased by relaxing the thermo-ON condition, and although there are cases of excessive air-conditioning capability leading to temporary instances of poor efficiency, this autonomous optimization takes effect in these cases as well, suppressing the loss of efficiency.

(3-7)

The indoor units **40**, **50**, **60** comprise respective indoor expansion valves **41**, **51**, **61** (an example of the expansion mechanisms) capable of adjusting the degrees of superheat or the degrees of subcooling in the outlet sides of the indoor heat exchangers **42**, **52**, **62**. The indoor-side control devices **47**, **57**, **67** adjust the opening degrees of the indoor expansion valves **41**, **51**, **61** in each indoor unit, reduce the degrees of superheat or the degrees of subcooling if the air-conditioning capabilities are excessive, and increase the degrees of superheat or the degrees of subcooling if the air-conditioning capabilities are insufficient. The air-conditioning capability can be autonomously optimized in each indoor unit by adjusting the opening degrees of the indoor expansion valves **41**, **51**, **61** in this manner. The number of thermo-ON indoor units is increased by relaxing the thermo-ON condition, and although there are cases of excessive

air-conditioning capability leading to temporary instances of poor efficiency, this autonomous optimization takes effect in these cases as well, suppressing the loss of efficiency.

(4) Modifications

(4-1) Modification 1A

In the above embodiment, the indoor-side control devices **47**, **57**, **67**, or the operation control device **80** including the indoor-side control devices **47**, **57**, **67** and the outdoor-side control device **37**, were given as examples of control devices, but examples of control devices are not limited thereto, and the control devices may be centralized controllers which acquire data from the outdoor unit **20** and the indoor units **40**, **50**, **60**, and which provide data to the outdoor unit **20** and the indoor units **40**, **50**, **60**. The entire air conditioning system is easily harmonized by the unifying management of the centralized controllers.

What is claimed is:

1. An air conditioning system, comprising:
a plurality of indoor units installed in a same indoor space,
the indoor units including respective usage-side heat exchangers and being capable of setting set temperatures individually;
an outdoor unit including a heat-source-side heat exchanger arranged and configured to conduct heat exchange with refrigerant circulating through the usage-side heat exchangers; and
a control device configured
to perform temperature control of the same indoor space by controlling each of the indoor units to be in a thermo-ON state when a thermo-ON condition is satisfied and to be in a thermo-OFF state when the thermo-ON condition is not satisfied, a separate thermo-ON condition being set in advance with respect to each of the indoor units in accordance with the respective set temperatures, the thermo-ON condition being a condition in which a predetermined temperature difference exists between the set temperature and a control temperature, the control temperature being an indoor temperature detected by an indoor temperature sensor,
to determine if at least one of the indoor units is in the thermo-ON state and at least one of the indoor units is in the thermo-OFF state,
to relax the thermo-ON condition of the at least one indoor unit determined to be in the thermo-OFF state by reducing the predetermined temperature difference of the thermo-ON condition of the at least one indoor unit determined to be in the thermo-OFF state when it has been determined that at least one of the indoor units is in the thermo-ON state and at least one of the indoor units is in the thermo-OFF state and a predetermined condition is satisfied, the predetermined condition being that at least one of the plurality of indoor units has been in the thermo-ON state continuously for a first elapsed time or longer, and at least one of the plurality of indoor units has been in the thermo-OFF state continuously for a second elapsed time or longer.
2. The air conditioning system according to claim 1, wherein
the control device relaxes the thermo-ON condition without altering a thermo-OFF condition.
3. The air conditioning system according to claim 1, wherein
the control device appoints an operating condition of the outdoor unit so as to satisfy a highest increase require-

25

ment of increase requirements of air-conditioning capability of the plurality of indoor units.

4. The air conditioning system according to claim 3, wherein

the control device has

a required temperature calculation unit configured to calculate required evaporation temperatures or required condensation temperatures of the usage-side heat exchanger for each of the indoor units, and a target value appointing unit configured to appoint

a target evaporation temperature based on a minimum value of the required evaporation temperatures of the indoor units calculated in the required temperature calculation units, or

a target condensation temperature based on a maximum value of the required condensation temperatures of the indoor units calculated in the required temperature calculation units.

5. The air conditioning system according to claim 1, wherein

the plurality of the indoor units further include respective air blowers useable to adjust airflow volumes directed to the usage-side heat exchangers; and

the control device adjusts the air blowers of the indoor units to reduce the airflow volumes when air-conditioning capabilities are excessive and to increase the airflow volumes when the air-conditioning capabilities are insufficient.

6. The air conditioning system according to claim 1, wherein

the indoor units further include respective expansion mechanisms capable of adjusting degrees of superheat or degrees of subcooling in the outlet sides of the usage-side heat exchangers; and

the control device adjusts the opening degrees of the expansion mechanisms in the indoor units to reduce the degrees of superheat or degrees of subcooling when the air-conditioning capabilities are excessive and to increase the degrees of superheat or degrees of subcooling when the air-conditioning capabilities are insufficient.

7. The air conditioning system according to claim 1, wherein

the control device is centralized controller that acquires data from the outdoor unit and a plurality of the indoor units and sends data to the outdoor unit and a plurality of the indoor units.

8. A method for controlling an air conditioning system including

a plurality of indoor units installed in a same indoor space, the indoor units including respective usage-side heat exchangers and being capable of setting set temperatures individually, and

an outdoor unit including a heat-source-side heat exchanger arranged and configured to conduct heat exchange with refrigerant circulating through the usage-side heat exchangers, the method comprising:

26

a first step of causing temperature control of the same indoor space to be performed by controlling each of the indoor units to be in a thermo-ON state when a thermo-ON condition is satisfied and to be in a thermo-OFF state when the thermo-ON condition is not satisfied, a thermo-ON condition being set in advance with respect to each of the indoor units in accordance with the set temperatures, the thermo-ON condition being a condition in which a predetermined temperature difference exists between the set temperature and a control temperature, the control temperature being an indoor temperature detected by an indoor temperature sensor; a second step of determining if at least one of the indoor units is in the thermo-ON state and at least one of the indoor units is in the thermo-OFF state; and a third step of relaxing the thermo-ON condition of the at least one indoor unit determined to be in the thermo-OFF state by reducing the predetermined temperature difference of the thermo-ON condition of the at least one indoor unit determined to be in the thermo-OFF state when it has been determined that at least one of the indoor units is in the thermo-ON state and at least one of the indoor units is in the thermo-OFF state and a predetermined condition is satisfied,

the predetermined condition being that at least one of the plurality of indoor units has been in the thermo-ON continuously for a first elapsed time or longer, and at least one of the plurality of indoor units has been in the thermo-OFF state continuously for a second elapsed time or longer.

9. The method for controlling an air conditioning system according to claim 8, further comprising

storing the predetermined temperature difference on a memory of a control device; and when the predetermined temperature difference is reduced, rewriting the predetermined temperature difference stored on the memory.

10. The method for controlling an air conditioning system according to claim 8, wherein

the control temperature of each of the indoor units being a temperature of indoor air drawn into the each indoor unit.

11. The air conditioning system according to claim 1, wherein

the control device includes a memory with the predetermined temperature difference stored thereon, and when the predetermined temperature difference is reduced the predetermined temperature difference stored on the memory is rewritten.

12. The air conditioning system according to claim 1, wherein

the control temperature of each of the indoor units being a temperature of indoor air drawn into the each indoor unit.
